(73) Assignee: **Gripple Limited**, Sheffield (GB)

Primary Examiner—Holly H. Baynham

Assistant Examiner—Sheryl Friedman

(**) Term: **14 Years**

(74) *Attorney, Agent, or Firm*—King & Schickli, PLLC

(21) Appl. No.: **29/250,171**

(57) **CLAIM**

(22) Filed: **Nov. 6, 2006**

The ornamental design of a wire termination, connecting and tensioning device, as shown and described.

(30) **Foreign Application Priority Data**

May 8, 2006 (EM) 000526793-0001

DESCRIPTION

(51) **LOC (8) Cl.** **08-08**

FIG. 1 is a view of the device from above one end and one side;

(52) **U.S. Cl.** **D8/383**

FIG. 2 is a view from above and the other end and from the same side;

(58) **Field of Classification Search** D8/382,

FIG. 3 is an elevation of the same side of the device, the opposite side being mirror image;

D8/383; 439/404, 409, 410, 417, 369; 24/115 R

FIG. 4 is an elevation of the device as seen from the left hand side of FIG. 3; the opposite side being a mirror image; and,

See application file for complete search history.

FIG. 5 is an elevation as seen from above FIG. 3.
